UNITED STATES PATENT OFFICE.

STACY B. HASELTINE, OF CHICAGO, ILLINOIS, ASSIGNOR TO W. H. MINER, INC., OF CHICAGO, ILLINOIS, A CORPORATION OF DELAWARE.

SHOCK-ABSORBING MECHANISM.

Application filed February 16, 1927. Serial No. 168,557.

This invention relates to improvements in shock absorbing mechanisms.

One object of the invention is to provide a tandem spring shock absorbing mechanism adapted for railway draft riggings, having the usual front and rear stop lugs, wherein is provided simple and efficient means for effecting compression of the springs in tandem, which at the same time serves to provide a column of unusual strength to limit approach of the main followers and prevent the springs from being unduly compressed.

Another object of the invention is to provide a tandem spring shock absorbing mechanism of the character indicated, of exceptionally rugged and substantial construction, comprising a minimum number of parts which may be readily assembled, and wherein in all of the parts of the mechanism proper other than the springs may be manufactured economically as ordinary foundry castings.

A still further object of the invention is to provide a tandem spring shock absorbing mechanism comprising only two relatively movable pressure transmitting members co-operating with the usual main followers, wherein the pressure transmitting members are in the form of telescoped castings, each having intermediate follower means formed as an integral part thereof.

Other objects of the invention will more fully and clearly appear from the description and claims hereinafter following.

In the drawings, forming a part of this specification, Figure 1 is a longitudinal horizontal sectional view of a portion of a railway draft rigging, showing my improvements in connection therewith. Figure 2 is a transverse vertical sectional view corresponding substantially to the line 2-2 of Figure 1. And Figure 3 is a detailed perspective view of a pressure transmitting member employed in connection with my improved mechanism.

In said drawings, 10-10 indicate channel-shaped center or draft sills of a railway car underframe, to the inner sides of which are secured front stop lugs 11-11 and rear stop lugs 12-12. The inner end of the drawbar is designated by 13, to which is operatively connected a yoke 14 of well known form.

The shock absorbing mechanism proper and front and rear main followers 15 and 16 are disposed within the yoke and the yoke

and the parts therewithin are supported in operative position by a detachable saddle plate 17 fixed to the draft sills.

My improved spring shock absorbing mechanism, which co-operates with the front and rear main followers 15 and 16, comprises broadly: A combined spring cage and intermediate follower A; a combined pressure transmitting member and intermediate follower B; and tandem arranged front and rear spring resistance elements C-C.

The combined spring cage and intermediate follower A comprises a rectangular casing having longitudinally disposed spaced vertical side walls 18-18 and longitudinally disposed horizontal spaced top and bottom walls 19-19. The casing A is open at the front and rear ends and has the rear end thereof bearing on the rear main follower 16 which is in the form of a heavy rectangular block co-operating with the stop lugs 12. The forward end of the casing A is spaced a distance from the inner side of the front main follower 15 corresponding to the permissible compression of the mechanism so that when the mechanism is fully compressed, the relative movement of the follower 15 and the casing A will be arrested, the casing acting as a solid stop column to transmit the actuating force to the draft sills. The casing A is also provided with a vertical web 20 formed integral with the top and bottom walls of the casing and spaced from the side walls 18, as clearly shown in Figures 1 and 2. The web 20 is disposed between the front and rear ends of the casing A and is nearest the front end thereof. The web 20 is reinforced by three vertically disposed ribs on the rear side thereof as clearly shown in Figure 1. The front face of the web 20 is flat and is adapted to bear on the inner ends of the coils of the front spring member of the tandem spring resistance elements C. The web 20 functions as a front intermediate follower. The combined pressure transmitting member and intermediate follower B comprise two longitudinally extending bar like arms 21-21 connected by a transverse web or section 22 which is reinforced on the front side thereof by horizontal ribs 23 clearly shown in Figure 3. The web 22 is disposed at the inner ends of the arms and is spaced a short distance from the inner extremities thereof as shown in Figures 1 and 2.

In the drawings, forming a part of this specification, Figure 1 is a longitudinal horizontal sectional view of a portion of a railway draft rigging, showing my improvements in connection therewith. Figure 2 is a transverse vertical sectional view corresponding substantially to the line 2-2 of Figure 1. And Figure 3 is a detailed perspective view of a pressure transmitting member employed in connection with my improved mechanism.

In said drawings, 10-10 indicate channel-shaped center or draft sills of a railway car underframe, to the inner sides of which are secured front stop lugs 11-11 and rear stop lugs 12-12. The inner end of the drawbar is designated by 13, to which is operatively connected a yoke 14 of well known form.

The shock absorbing mechanism proper and front and rear main followers 15 and 16 are disposed within the yoke and the yoke

and the parts therewithin are supported in operative position by a detachable saddle plate 17 fixed to the draft sills.

and 3, thereby providing a seat or socket for the front end of the rear member of the twin spring resistance elements C. The side arms 21 have flat outer faces which bear on the 5 side walls 18 of the casing A. On the inner sides, the members 21 are cut away to provide concave surfaces adapted to accommodate the outer side portions of the larger outer coil of the front member of the twin 10 springs. The rear face of the transverse web 22 is substantially flat as clearly shown in Figure 1, and bears on the outer ends of the two coils of the rear member of the tandem springs. The combined pressure transmitting member and intermediate follower B is 15 assembled with the casing A by inserting the former through the rear end of the casing, thus telescoping the same therewith, so that the arms 21 will straddle the vertical 20 web 20 of the casing A. The front ends of the arms 21 bear on the inner side of the front main follower 15.

The tandem arranged spring resistance elements comprise front and rear members 25 C, each consisting of a relatively light inner coil and a heavier outer coil. The two coils of the front member C have their front ends bearing on the main follower 15 and their rear ends bearing on the front side of the 30 transverse web 20 which functions as a front intermediate follower and the two coils of the rear spring resistance element C have the front ends thereof bearing on the transverse web 22 of the member B, said web functioning as a rear intermediate follower. The two 35 coils of the last named spring resistance have their rear ends bearing directly on the rear main follower 16.

The operation of my improved shock absorbing mechanism, assuming a compression stroke, is as follows: The main followers 15 and 16 will be moved relatively toward each other, thereby moving the pressure transmitting member B inwardly of the casing A, compressing the front main spring C between 40 the front follower 15 and the front intermediate follower 20 and the rear main spring C between the rear main follower 16 and the rear intermediate follower 22. Compression 45 of the mechanism will continue either until the actuating force is reduced, or until relative approach of the main followers 15 and 16 is limited by engagement of the main follower 15 with the front end of the casing A, where- 50 upon the actuating force will be transmitted directly through the casing A which acts as a solid stop column. Upon the actuating pressure being reduced, the tandem springs 55 will restore the parts to the normal position shown in Figure 1.

While I have herein shown and described what I now consider the preferred manner of carrying out my invention, the same is merely illustrative, and I contemplate all

changes and modifications that come within 65 the scope of the claims appended hereto.

I claim:

1. In a tandem spring shock absorbing mechanism adapted for co-operation with the usual front and rear main followers of a 70 railway draft rigging, the combination with a casing open at opposite ends and adapted to bear on one of said main followers, said casing having intermediate follower means thereon; of a pressure transmitting member telescoped within said casing, said pressure transmitting member including arms spanning the intermediate follower of said casing, the outer ends of said arms being adapted to bear on the other main follower; a second intermediate follower serving as a connecting section for said arms; and tandem arranged springs, one of said tandem springs being interposed between the main 75 follower on which said casing bears and the second named intermediate follower, and the other tandem spring being interposed between said first named intermediate follower and the remaining main follower. 80

2. In a tandem spring shock absorbing mechanism, the combination with front and rear main followers; of a rectangular casing open at both ends and bearing on one of said main followers, said casing being provided with an integral 90 intermediate follower connected to two opposed walls of the casing and spaced from the remaining walls thereof; a second intermediate follower having arms formed integral therewith and spanning the first named intermediate follower, said arms being disposed within said casing and having the outer ends bearing on the other main follower; and tandem arranged spring resistance 95 means, one of said spring resistance means being interposed between the first named intermediate follower and the main follower on which the arms bear, and the other spring resistance means being interposed between the second named intermediate follower and the main follower on which the casing bears. 100

3. As an article of manufacture, a one-piece pressure transmitting member and casing for a tandem draft rigging, said casing being of hollow tubular construction open at each end and provided on the interior thereof at a point adjacent, but to one side of the center thereof with an integral partition adapted to serve as an intermediate 115 follower, said partition being spaced at its sides from adjacent walls of the casing to thereby permit the straddling of the partition by portions of another element. 120

In witness that I claim the foregoing I have hereunto subscribed my name this 11th day of February, 1927.

STACY B. HASELTINE.
